DESIGN FOR A CIGARETTE CASE OR SIMILAR ARTICLE

Fulco di Verdura, New York, N. Y., assignor to Paul E. Flato, New York, N. Y.

Application December 7, 1937, Serial No. 73,419

Term of patent 3½ years

To all whom it may concern:

Be it known that Fulco di Verdura, a subject of Italy and resident of New York, in the county of New York and State of New York, has invented a new, original, and ornamental Design for a Cigarette Case or Similar Article, of which the following is a specification, reference being had to the accompanying drawing, forming part thereof, in which,

Fig. 1 is a plan elevational view of a cigarette case or similar article embodying my design;

Fig. 2 is a rear end view thereof;
Fig. 3 is a side end view thereof;
Fig. 4 is a front end view thereof; and
Fig. 5 is a bottom elevational view thereof.
I claim:
The ornamental design for a cigarette case or similar article, substantially as shown.

FULCO DI VERDURA.
